WORK GRIPPING AND DRAWING MECHANISM FOR SHEET SHAPING MACHINES OPERATING ON THE FORMING-BY-DRAWING PRINCIPLE

Frohman Anderson, Las Vegas, Nev.

Original application February 8, 1955, Serial No. 486,773, now Patent No. 2,851,080, dated September 9, 1958. Divided and this application December 24, 1957, Serial No. 704,934

21 Claims. (Cl. 153—32)

This application is a division of application Serial No. 486,773, filed February 8, 1955, now Patent No. 2,851,080, which relates to a machine for shaping metal sheets into compound curves by pulling the sheets edge-wise from one end to the other over a series of forming elements the working faces of which differ in contour transversely of the sheets and are disposed in stepped relation, a restraining or hold-back force being exerted on the sheets in opposition to the pulling force to subject the sheets to stresses beyond their yield point. This operation in the said parent application is termed forming-by-drawing.

Such machines are composed of three main functional components comprising the sheet forming structure, a draw bench including a power-actuated carriage for the mechanism that is to be translated in the performance of the operation, and the sheet pulling mechanism attached to and propelled by the carriage for gripping and drawing the sheets through the forming structure.

This application relates to the last-mentioned component, that is, the pulling mechanism for drawing the work through the sheet forming structure.

The translatable part of the pulling mechanism is moved by the power-actuated carriage and includes a draw head with a series of jaws for gripping the leading edge of the sheet, and a draw arm attached to the reciprocating carriage and coupled to the draw head through a coupling that may include a lost motion feature to allow a limited motion of the arm relative to the draw head at the beginning and end of each cycle.

The jaws are operated through hydraulic power, being automatically closed at their pick-up position to grip the sheet and automatically opened to discharge the sheet at the end of the drawing half cycle.

The gripping elements of the jaws are plates that slide in converging grooves and are urged forward and back by a hydraulically-operated piston. The jaws are so mounted that they may be raised and lowered collectively and also individually and they may also be angularly adjusted to bring them into conformity with the elevation and angle of the immediate portion of the edge of the sheet.

The hydraulic system for operating the jaws includes a motor-driven pump and a control valve for selectively connecting the jaw-operating pistons to the high and low pressure sides of the hydraulic system. The control valve is automatically reversed at the end of the movement of the draw head and jaws in each direction through the instrumentality of limit switches. Alternatively, the reversing of the control valve may be effected through manual switches.

Specifically, the control valve is spring-biased to one position and is moved to the opposite position by a solenoid the energization of which is controlled by the limit switches.

Provision is made to disable a certain number of the jaws on each end of the series so that the number of effective jaws may be adjusted to the width of the sheet

being drawn. Specifically, this is done through manual shut-off valves, a valve being provided in the hydraulic connection with each of the particular jaws.

The invention comprehends other features of construction and has other objects and advantages as will appear from the following particular description of the embodiment of the invention illustrated in the accompanying drawings, to which reference will now be made.

Fig. 16 is a diagram of the portion of the electrical system of the machine in control of the hydraulic valve and pump for the hydraulic system for operating the jaws.

In the construction shown, the draw bench and carriage slidably therein are disposed at one side of the forming structure and the draw arm is attached at one end to the carriage and extends laterally in front of the forming structure.

The forming structure is in the main contained between two uprights and has a rearward extension which incidentally serves as a supporting table and guide for the work sheets as they are fed into the machine.

The base is of irregular shape and consists of a sub base 11 on the left end of which in respect to the direction of feed are mounted a gear box 12 and the main drive motor 13 and the gear reduction and coupling 14. On the other end of the sub base is mounted a main base 15 a portion of which is shown in Figs. 3 and 4 and which supports the forming structure of the machine.

The two uprights 16 and 17 for the forming structure are secured to the sub base and to the main base which is also contained between the uprights. The forming structure is composed of three stages the first of which has upper and lower elements which cooperate to form a slot the width of which may be varied for different thicknesses of metal and which determines the general path

of movement of the work. This first stage imposes a restraint on the sheet and is known as the hold-back stage.

The second stage has a draw-over forming element

which is disposed in front of the first stage, that is, beyond the first stage in the direction of draw. The working face of the second stage forming element is in stepped relation to the first stage slot and differs in shape or contour from that of the slot. In most cases the slot is straight and the second stage forming element is curved either up or down, depending upon the desired result, and the second stage element is below the slot so that the sheet bends down as it emerges from the slot.

The third-stage forming element is also a draw-over element having a work face of the same geometrical shape as the second stage element with its working face disposed just beyond the second stage element and stepped in relation thereto at an elevation between that of the first and second stage elements. The sheet is drawn over the second and third stage elements in such a manner that the two elements engage the sheet on opposite sides.

The lower portion of the first stage structure comprises a T-shaped member having a transverse head 18 having a work engaging element 19 secured on its top face by a clamp 20, and back of the work engaging element is a smoothing plate 21 secured on the head by a clamp 22. The cross head 18 is attached at its ends to secondary uprights 23 and 24 which are interiorly adjacent uprights 16 and 17, respectively, and have articulated bearings therein (not shown).

This T-shaped lower member has a rearwardly extending leg 25 which is connected to the piston of a hydraulic motor 26 through a pivoted crank 27 and links 28. The T-shaped lower member is thus given a forward and back dynamic movement for reasons not pertinent to this invention. In this movement the T-shaped member is supported to slide upon a universally mounted guide structure 29.

The upper portion of the first stage or hold-back structure includes a transversely extending ram 30 which opposes head 18 and element 19 with an upper work engaging element 31 secured to the ram by clamp 32. Back of the element 31 is a smoothing plate 33 which opposes plate 21.

The ram 30 slides on secondary uprights 23 and 24 in gibs 34, and is raised and lowered by a hydraulic motor 35 (Fig. 2) through toggles attached to the ram at their lower end and at their upper end to a fixed cross bar 36 connecting the tops of secondary uprights 23 and 24. The raising and lowering of the ram is automatically controlled through mechanism not shown. It is raised when a sheet S is fed into the machine and is lowered as the pull begins.

The second stage also includes a ram 37 which has a work engaging element 38 secured on its lower face and having an upwardly curved work engaging face on its bottom edge which is disposed with its longitudinal center below the exit slot of the first stage. The ram 37 is raised and lowered by toggles connected to a cross bar 39 spanning uprights 16 and 17 and operated by an hydraulic motor 40 (Fig. 2) which is automatically controlled through mechanism not shown. The ram 37 is guided in gibs on the uprights.

The third stage structure has also a T-shaped body member including a cross head 41 and a rearwardly extending leg 42. The cross head 41 carries a forming element 43 which opposes the second stage element 38 and has on its upper edge a work engaging face of the same contour as that of the second stage but slightly higher and in front thereof. The cross head 41 has a longitudinal oil-collecting groove 41a in its front face which communicates with an oil passage leading to a sump in the base, as shown in Fig. 4. The functioning of these forming elements is fully described in the said parent application.

The third stage rests upon and is slidably supported by the main base 15 and also has potential dynamic adjustment forward and back through motive power (not shown).

The draw bench structure in the embodiment shown is disposed at one side of the forming structure. It consists primarily of an elongated stationary channel-shaped bench member 44 which is supported at a mid point on the gear box 12, and serves as a guide for a carriage 45 slideable therein. The bench 44 abuts and is keyed to the upright 16. Elsewhere the bench is supported by legs 46.

On the under face of the carriage is a rack 47 which 10 is engaged by a bull gear 48 in the gear box 12 operatively connected to the motor 13 through reduction gearing in the gear box. The motor is automatically controlled through means not shown, and actuates the bull gear in a manner to reciprocate the carriage according to 15 operational requirements.

The sheet pulling or drawing mechanism basically 20 comprises a laterally extending wing-shaped draw arm 49, which is attached to and reciprocated by the carriage 45, and a draw head 50 carried by the draw arm 49 together with a local hydraulic system including motor, 25 tank and valve mechanism carried by the arm.

The wing-shaped draw arm 49 comprises a flat bottom plate 51 which is fastened at its one end to the carriage 45. For attachment to the carriage the plate is provided 30 on its underside at that end with a depending boss 52 making a thickened portion which is of a width to enter between the vertical sides of the draw bench 44 and of a thickness to contact the carriage with the plate just clearing the draw bench, as shown in Figs. 1 and 15. This thickened portion of the plate is keyed to the carriage by keys 53 and is also bolted to the carriage as indicated in Fig. 5.

The plate 51 is subjected to the entire pulling force 35 of the sheets and it is reinforced by a streamlined concave top cover sheet 54 which makes in effect a hollow wing or arm that extends across in front of the forming mechanism. The plate or arm is widest at its attached end and is rounded on its forward edge to a narrower width at its free end at which end the cover sheet 54 steps down in two steps to a substantially thinner construction. This free end is supported in its reciprocation by a leg 40 55 which has a caster on its bottom end that runs on a rail 56 flush with the foundation.

The plate 51 has integrally secured on its under side 45 two pairs of channel-shaped guides for supporting and guiding a frame structure that extends forwardly from the draw head 50 and the frame structure has a limited freedom of movement in the guides, as will be seen. One pair of channel guides is numbered 57 and is on the front 50 edge of the plate extending forwardly therefrom somewhat nearer the narrow end than the wide end of the plate. This forward extension is enclosed by suitable cover plates which include an end cap closure 58 into which the front extremity of the frame reciprocates.

55 The other pair of channel guides for the frame are numbered 59 (Figs. 3 and 5) and are at the rear edge of plate 51 parallel with guides 57 but more widely spaced.

The guide frame of the draw head structure comprises 60 two forwardly converging channel bars 60 and 61 which are attached to the draw head 50 at their rear ends and come together in a V-structure. The flanges of the bars are disposed top and bottom with the web outside, and the top and bottom flanges merge at the juncture until the webs meet and continue forwardly face to face into the 65 cap 58. The frame has two plates secured upon its top face which serve as crossheads guided in the guides 57 and 59. The rear plate 62 is relatively wide and slides in guide 59, suitable bearings 62a, such as formica, being provided, as indicated by the stippling in Fig. 5. The forward plate 63 is of a width to slide in guides 57 which have similar bearings. Depending from the bottom side of plate 51 is an abutment block 64 disposed between plates 62 and 63 and located so that it abuts against the rear edge of plate 63 on the draw but near the end of the return half of the cycle it is free to move with its 70 75

supporting plate 51 away from the plate 63 after the jaws arrive at the sheet-gripping position. It will be seen that this relative movement is necessary in the cycle of operation, but the spacing is such that the block 64 stops short of contact with the plate 62. Fig. 5 represents the most rearward position of the plate 51 with the jaws in initial gripping position. Through means not here shown, the carriage is caused to slow down as the jaws approach the edge of the sheet and there is a definite stop for the jaw head at the correct gripping position, while the plate or draw arm continues on for a short distance before the carriage is stopped and reversed, and then the arm moves forwardly far enough for the block 64 to pick up plate 63 before the draw begins.

The draw head construction 50 will now be described. At their rear ends the frame bars 60 and 61 are secured against the forward face of a vertical plate 65 having a vertical rear face 65a which serves as the supporting and adjusting face for the jaw assembly. On the bottom of plate 65 is secured the rear edge of a horizontal plate 66 which has rounded forward corners, as shown in Fig. 5. This plate 66 extends from end to end of plate 65 and underlies and is secured to the bars 60 and 61. A similar top plate 67 is secured at its rear edge to the top of plate 65 and is also secured on the top flanges of bars 60 and 61. Secured between the forward edges of plates 66 and 67 are vertical plates 68 and 69 which extend laterally from and are secured to the webs of bars 60 and 61, respectively. Thus there is provided an open-ended housing in front of and mounting the jaw assembly which serves as a truss as well as a housing for hydraulic manifolds and tubing.

The vertical plate 65 has a series of four through bolts 70 which pass through vertically elongated holes 71 and screw into a vertically adjustable jaw holder bar 72 which bears on vertical guide face 65a (see Figs. 3 and 6). On each end of bar 72 is a vertically threaded extension 73 circular in cross-section (see Fig. 4) in which is a manually adjustable screw 74 that bears on its lower end against the top of a rearward extending shoulder member 75 that is secured on each end of plate 65. It will thus be seen that screwing down on screws 74 will raise the bar 72 and all of the jaws as a unit, while screwing out on the screws will allow the bar 72 and the jaws to drop as a unit. The elongated holes 71 permit of such adjustment relative to the plate 65, it being necessary to loosen the bolts 70 to release the bar for such adjustment, the bolts being again tightened after each adjustment. Wrench holes 76 are provided in the bottom plate 66 in registry with each bolt to accommodate the tool for turning the bolts.

There are shown twelve individual jaws each designated as a whole by the numeral 77. Secured on the top and bottom of the bar 72 are twelve equally spaced screw-retaining plates 78 and 79, respectively, being keyed thereto by keys 80 and 81, respectively, and otherwise secured as by screws (not shown). The plates 78 and 79 are somewhat longer than the width of bar 72 so that their ends extend beyond the rear face of bar 72 and thereby provide a top and bottom longitudinal projection on the rear or supporting face of bar 72, this face being thus made channel shape with the projections in effect constituting the flanges for the channel, as shown in Figs. 4 and 6. The gripping mechanism of the jaws is rotatively mounted in a hub member 82 so as to turn therein on a horizontal axis for the purpose of adjusting the jaws to the angle of the leading edge of the sheet. The hub member is shown as circular in cross-section and is vertically tapped to provide a threaded vertical opening therethrough to receive an adjusting screw 83. This adjusting screw has reduced ends which bear in the overhanging extensions of plates 78 and 79, the upper end being slotted for a tool. Therefore, by turning the screw 83, the hub 82 and the jaw carried thereby are adjusted

vertically, means being thereby provided for individual vertical adjustment of the jaws relative to the bar 72.

The jaw structure itself is shown in detail in Figs. 6 through 12. A rectangular solid body member 84 has two side plates 85 and 86 bolted thereto and keyed by keys 84a. The body member has a central axis bore forming a cylindrical cavity 184a closed at its forward end by a screw plug 87 and constituting a closing head on that end to form a hydraulic cylinder in which is reciprocated a piston 88.

Spanning the side plates 85 and 86 and bolted thereto are rearwardly converging top and bottom plates 89 and 90, respectively. As shown, these plates 89 and 90 are set in grooves in the inner faces of the plates 85 and 86 and form backing members and guides for top and bottom jaws or gripping plates 91 and 92, respectively, the side edges of which occupy the space between the bottoms of the grooves in the side plates and the backing plates. The gripping plates are beveled off and serrated at their ends to enhance their grip upon the edge of the sheet. The side plates have circular cut-outs 93 providing a mouth for the admission of the edge of the sheet.

For actuation the gripping plates are connected by a circular key or coupling member 94 which is seated at its ends in round bores constituting key receiving holes in the gripping plates. This key 94 (Fig. 12) has a diametrical bore 94a which is screw-threaded and receives the reduced threaded end of the piston rod 95. The rear end of the cylinder is closed by a permanent head plug 96 which has an internal piston ring surrounding the piston rod 95, the body member 84 having a rearwardly extending rectangular neck portion 84b into which the head plug 96 hermetically fits and is secured. Thus, it will be seen that admission of pressure fluid on the right side of piston 88 as viewed in Fig. 8 will force the piston to the left and draw the plates up the inclined guide grooves and open the jaws; while pressure fluid on the left of the piston will force it to the right and close the jaws, which is the position shown in Fig. 8. The length of the gripping plates 91 and 92 is such as to allow of this movement in the side plate grooves.

The body member 84 has a threaded reduced cylindrical axial extension 97 on its forward face which screws into a threaded socket on the hub member 82. The wall of this socket is split, as shown in Fig. 9 and is expanded and contracted by a clamping screw 98. The angular position of the jaw may be adjusted when the screw is loosened and it is locked in adjusted position when the screw is tightened.

There are two hydraulic tubes 99 and 100 attached to the body member 84 and communicating with passages in the body member leading to opposite ends of the cylinder. As shown, tube 99 connects with passage 99a leading to the end at the left of piston 88 in Fig. 8 and tube 100 connects with passage 100a leading to the end of the cylinder at the right of the piston in Fig. 8. These tubes 99 and 100 connect with manifolds 101 and 102, respectively, which are housed within the housing in front of vertical plate 65. Two tubes 103 and 104 connect with manifolds 101 and 102, respectively, and are carried by the channel frame structure for the draw head and connect with correspondingly numbered flexible extensions leading to the valve and pump mechanism carried by the arm 49, the flexible portion of the tubing being to allow for the relative movement between the arm and the draw head with its guide frame.

The hydraulic pump and valve mechanism is shown particularly in Figs. 5, 13 and 14. It is suspended underneath the plate 51 on a hanger plate 105 that has at its forward end an upstanding arm 106 and 107 on the respective sides with outturned top extension 108 and 109, respectively, that are riveted or bolted to the underside of plate 51. At an intermediate level in front is a valve supporting plate 110. An extension of plate 105 at the

rear end is attached to plate 51 by a bolt 111, suitable spacing means (not shown) being provided.

A motor M4 is seated on plate 105 and operates a pump 112 which is connected into tank 113 which contains the hydraulic fluid.

The valve, designated as a whole by the numeral 114, is shown in detail in Fig. 14 and is seated upon plate 110. The valve proper has a case 115 and a slidable spool 116. The spool is urged in one direction by a spring 117 and in the other direction by a solenoid S4. The valve has four ports, one of which is connected to the pressure side of the pump by tube 118 and another of which is connected to the return to the tank through pipe 119. Of the other two ports one is connected to pipe 103 and the other to pipe 104. When the spool is in the position at the left as shown in Fig. 14 to which it is moved by the spring, the pressure fluid is connected to tube 103 while tube 104 is connected to the low pressure or return; and when the spool is moved to the right under the influence of the solenoid, the connections to the jaws are reversed, tube 104 being pressure and 103 being return.

It will be seen that when the solenoid is de-energized and the spring is in control of the valve, the jaws are closed for the reason that the pressure is admitted to the left end of the cylinders in the jaws as shown in Fig. 8 through tube 103, manifold 101 and tube 99; and that when the solenoid is energized the valves are open since the pressure is in the right end of the cylinders through tube 104, manifold 102 and tube 100.

The operating of the valve is effected by automatic control of the energization of the solenoid at controlled times in the cycle, and may also be effected manually through push buttons connected in parallel to the automatic controls, as will now be described with especial reference to Fig. 15.

Fig. 16 shows the electrical circuit for the motor M4 and solenoid S4. Associated with the draw head 50 is an adjustable positive stop member shown as a flat bar 120 (see especially Fig. 3). This bar is disposed under the jaw assembly at substantially the center line of the jaws and is supported in a guide channel 121 on the underside of plate 66. The forward end of the bar is rounded and screw-threaded and extends through the depending flange of an angle bracket 122, the horizontal flange of which is bolted to an arm 123 that is bolted onto the bottom plate 66 and extends forwardly over the bracket. The bolt 124 which secures the bracket 122 to the arm 123 extends through a slotted opening in the arm to allow of adjustment of the bar 120. Two nuts on the opposite sides of the bracket flange provide for the longitudinal adjustment of the bar, and the bar is positioned so that its contact end enters into the oil groove 41a in the third stage crosshead 41 at the limit of return or pick-up movement of the jaws. The jaw assembly moves very smoothly on the formica bearings and the bar is not subjected to any great impact force, although it serves to limit the movement with required exactness and accurately position the jaws to grip the edge of the sheet. An adjustable abutment screw 125 in a depending flange on the end of arm 123 bears against the flange of bracket 122 and braces the bracket on impact.

A spring plunger 126 on the end of bar 120 operates a micro limit switch LS7 which is normally closed and is opened by the contact pressure on the plunger against the spring. This opening of switch LS7 deenergizes solenoid S4 and spring 117 moves the valve plunger or spool to the left in Fig. 14 and connects the pressure into line 103 and closes the jaws.

Carried by the wing arm 49 is another limit switch LS8 which is normally open and at the portion of the cycle near the end of the draw this limit switch LS8 strikes a dog 127 adjustable on a bar 128 on the side of the draw bench and closes the circuit of relay 4S which controls solenoid S4 and closes the solenoid cir-

cuit. As will later be seen, a holding circuit keeps the solenoid energized until the switch LS7 is again opened. The energization of solenoid S4 causes the valve plunger to move to the right and connect the pressure into line 104 and open the jaws.

To enable manual operation of the jaws the circuit for the relay 4S includes two push buttons 129 and 130 on the outer end of wing arm 49. Button 129 normally closes its switch contacts which are in series relation to LS7 and button 130 is in normally open relation to the contacts which are in parallel relation to LS8.

Bus bars 131 are laid in the inner faces of the upright sides of the draw bench and brushes 132 are carried by the carriage 45 and wipe the bus bars. The bus bars are connected across a source of A.C. current and the brushes connect the circuit for the solenoid, relay and motor M4 to the bus bars, as shown in the diagram of Fig. 16.

The two A.C. conductors are numbered 133 and 134. The relay 4M for motor M4 is connected across the line 20 through the button 135. If the button is closed the relay 4M is energized, closing contacts 4M1 and 4M2 which connect conductors 136 and 137 to the respective sides of the main line. This energizes motor M4 which is connected across wires 136 and 137 and the motor will 25 continue to run and operate pump 112 until switch 135 is opened.

The energizing of relay 4S will energize the solenoid S4. In the condition shown in Fig. 16 the relay 4S is deenergized and the solenoid S4 is deenergized, leaving spring 117 in control of valve 114 and holding the jaws closed. This is the condition during the draw until the dog 127 engages limit switch LS8 and momentarily closes it. This closes the circuit through relay 4S by way of line 136, switch LS7, wire 138, button 129, wire 139, switch LS8, and wires 140 and 141 including the relay to line 137. The relay thereupon closes switches 4S1 and 4S2. Switch 4S1 closes the circuit of solenoid S4 through wire 142, switch 4S1 and wire 143 to the other side of the line through solenoid S4. Normally open switch LS8 reopens at once but relay switch 4S2 holds the relay circuit closed through wire 138, wire 144, switch 4S2, wire 145, wire 140 and wire 141 including relay 4S. This condition remains until the holding circuit is broken either by the opening of switch LS7 or the opening of the switch controlled by button 129. The closing of the switch controlled by button 130 will also close the circuit for relay 4S.

While the entire twelve jaws will be required for sheets of maximum width, for narrower sheets a lesser number of jaws will be needed and, as shown in Fig. 13, for example, the outer four jaws at each end are provided with shut-off valves in their connection with the manifolds whereby one or more of the four may be made inoperative.

It will be understood that the details of the construction of the jaws and their supports and of the particular controls for the operating hydraulic system as shown in the drawings and above particularly described, are merely illustrative of the invention as required by statute, and that other equivalent embodiments will readily occur to those skilled in the art within the scope of the invention as defined in the following claims.

What is claimed is:

1. A forming-by-drawing machine comprising a pair of uprights, a forming element support spanning the uprights, a draw bench beside one of the uprights, a carriage slidable in the draw bench, power means connected to reciprocate the carriage, a wing plate attached to and movable with the carriage and extending laterally from the draw bench in front of the forming element support, guides on the wing plate, a jaw supporting frame slidable in the guides, and abutment members on the frame and wing plate engageable to transmit motion of the wing plate away from the forming element support to the frame.

2. A forming-by-drawing machine as defined in claim 1 in which the abutment members comprise a block fixed on the plate and a member on the frame sliding in and guided by the guides.

3. A forming-by-drawing machine as defined in claim 1 in which the guides comprise parallel rails on one face of the wing plate and the frame comprises diverging channel members, together with two spaced cross plates secured thereon and fitting within and slideable upon the guides, the front cross plate constituting one of the abutment members, and in which the other abutment member is a block secured on the said one face of the wing plate between the two cross plates.

4. A forming-by-drawing machine as defined in claim 3 in which the guides are channel members on the bottom face of the wing plate and support the jaw supporting frame guided thereon.

5. In a forming-by-drawing machine having uprights and opposed forming elements therebetween providing a discharge slot for a work piece and a draw bench and a carriage reciprocable therein at one side of the uprights and a wing plate extending laterally from the carriage in front of the discharge slot, a draw head carried by the wing plate and comprising a plurality of jaws positionable to engage and grip a work piece emerging from the slot, hydraulic means to open and close the jaws, a valve in control of the hydraulic means, and trip means for actuating the valve operative by movement of the carriage.

6. A draw head as defined in claim 5 in which the hydraulic means comprise a system including a hydraulic pump, two manifolds, a conduit connecting each manifold to each jaw, two conduits, one connected to each manifold, and said control valve having jaws opening and jaw closing positions and operative in alternate positions to connect the high and low pressure sides of the pump reversely to the said two conduits.

7. A draw head as defined in claim 6 in which the valve includes a spring biasing the plunger in one direction and a solenoid operative on the plunger in opposition to the spring.

8. A draw head as defined in claim 7 in which the spring biases the valve plunger to a jaw closing position and the solenoid when energized moves the plunger to a jaw opening position.

9. A draw head as defined in claim 7 together with an electric circuit for the solenoid including a control relay, circuit connections for the relay including a normally closed and a normally open switch, trip means engageable with one of the forming elements to open the normally closed switch at the limit of movement of the head toward the forming elements and trip means on the draw bench positioned to engage and close the normally open switch at the conclusion of the draw.

10. In a forming-by-drawing machine having uprights and opposed forming elements therebetween providing a discharge slot for a work piece and a draw bench and a carriage reciprocable therein transversely of the forming elements and a plate carried by the carriage in front of the discharge slot, a draw head carried by the plate and comprising supporting arms, a mounting plate on the arming having a vertical guide face, a jaw holding bar supported upon and guided by said guide face, means to raise and lower the bar relative to said plate, and a plurality of jaws carried by said holding bar.

11. In a forming-by-drawing machine having uprights and opposed forming elements therebetween providing a discharge slot for a work piece and a draw bench and a carriage reciprocable therein transversely of the forming elements and a plate carried by the carriage in front of the discharge slot, a draw head carried by the plate and comprising supporting arms, a mounting plate on the arms having a vertical guide face, a jaw holding bar supported upon and guided by said guide face, means to raise and lower the bar relative to said plate, a plurality

of jaws, and individual means for attaching each jaw to the holding bar, said individual attaching means including screw means to adjust the jaw vertically relative to the holding bar.

12. A draw head as defined in claim 11 in which the holding bar has a top and bottom longitudinal projection on its supporting face, together with an attaching hub on each jaw, the hub having a threaded vertical opening therethrough, and an adjusting screw in said threaded opening having its ends bearing in said projections.

13. A draw head as defined in claim 12 in which the jaw is rotatively adjustable in said hub.

14. In a forming-by-drawing machine having uprights and opposed forming elements therebetween providing a discharge slot for a work piece and a draw bench and a carriage reciprocable therein transversely of the forming elements and a plate carried by the carriage in front of the discharge slot, a draw head carried by the plate and comprising supporting arms, a mounting plate on the arms having a vertical guide face and a bearing arm extending toward the forming elements at each end and having spaced vertical slots therein, a jaw holding bar, headed screws passing through the slots and screwed into the holding bar and adjustably securing the bar to the mounting plate against the said vertical guide face, the bar being of a length to fit it between the bearing arms and having an extension on each end overhanging said arms, adjusting hand screws threaded through said extensions and bearing upon the respective arms, and jaws secured to the rear face of the bar.

15. The draw head construction defined in claim 14 in which the rear face of the holding bar is longitudinally channeled and the jaws have vertically tapped hubs disposed in said channel, together with adjusting screws engaging in the tapped hubs and bearing in the channel flanges.

16. The draw head construction defined in claim 15 in which the jaws are rotatively adjustable in their hubs.

17. In a forming-by-drawing machine, a jaw structure for gripping the leading edge of a work piece to draw it through the forming elements comprising a jaw body having guide grooves converging toward the gripping end, work piece engaging jaw plates slideable in said grooves with their inner faces angularly disposed and having key 45 receiving holes symmetrically disposed therein intermediate the ends of the plates, a key member extending between the plates and having its ends entered into said holes, the jaw body having an axial cylindrical cavity in its end opposite the gripping end, heads on the ends of 50 the cavity forming a closed cylinder, a piston reciprocable in the cylinder and having a rod connected to said key member, and passages through the body leading to the opposite ends of the cylinder for introducing or relieving pressure therein.

18. A jaw structure as defined in claim 17 in which the grooves are in side plates, together with converging plates attached to the side plates and backing the jaw plates.

19. A jaw structure as defined in claim 18 in which the key member has its ends beveled to the taper of the 60 grooves and is of a length to permit outward movement of the jaw plates to work gripping position without interference with the said backing plates, and with a diametrical threaded opening into which the end of the piston rod has threaded engagement.

20. A jaw structure as defined in claim 17 in which the end of the jaw body opposite the gripping end has a threaded cylindrical axial extension, together with an attaching hub member having an internally threaded collar extension into which the threaded extension on the jaw body engages.

21. A jaw structure as defined in claim 20 in which the said collar extension is split, together with a clamping screw through the split ends for releasing or applying clamping engagement of the collar about the threaded

extension to permit or restrain angular adjustment of the jaw.
